US00D994755S

(12) United States Design Patent (10) Patent No.: US D994,755 S
(45) Date of Patent: * Aug. 8, 2023

(54) CURVED SOFT BOX

(71) Applicant: Adorama Camera, Inc., New York, NY (US)

(72) Inventor: Joseph Mendlowits, New York, NY (US)

(73) Assignee: Adorama Camera, Inc., New York, NY (US)

() Term: 15 Years

(21) Appl. No.: 29/741,446

(22) Filed: Jul. 13, 2020

(51) LOC (14) Cl. 16-05

(52) U.S. Cl.

USPC D16/245; D16/237; D26/108;

(57) CLAIM

The ornamental design for a CURVED SOFT BOX, as shown and described.

DESCRIPTION

FIG. 1 is a perspective top view of a CURVED SOFT BOX showing my new design;

FIG. 2 is a perspective bottom view thereof;

FIG. 3 is a top view thereof;

FIG. 4 is a bottom view thereof;

FIG. 5 is a right side view thereof;

FIG. 6 is a left side view thereof;

FIG. 7 is a first end view thereof;

FIG. 8 is a second, opposite, end view thereof;

FIG. 9 is a perspective top view thereof showing the CURVED SOFT BOX in an alternate configuration; and

FIG. 10 is a perspective side view thereof shown in a state of use.

The broken lines shown in FIG. 10 depict environment and form no part of the claimed design.

1 Claim, 8 Drawing Sheets
